UNITED STATES PATENT OFFICE.

EDWIN M. BASSLER, OF MILWAUKEE, WISCONSIN.

SPRAYING APPARATUS.

Application filed December 8, 1921. Serial No. 520,801.

To all whom it may concern:

Be it known that I, EDWIN M. BASSLER, a citizen of the United States, and resident of Milwaukee, in the county of Milwaukee and State of Wisconsin, have invented a new and useful Spraying Apparatus, of which the following is a specification.

This invention relates to spraying apparatus.

10 Primary objects of the invention are, to provide spraying apparatus adapted for converting into spray liquids of practically all kinds, regardless of their consistency—whether thick or thin—and also regardless 15 of whether they contain impurities or foreign matter in suspension, either granular or stringy, which might tend to clog the apparatus and seriously impair, or entirely prevent its operation;

20 To provide spraying apparatus constructed and arranged for projecting the spray particles outwardly at high velocity, thus rendering the same particularly well adapted for scrubbing and clarifying air and gas 25 by removing therefrom dust and other solid particles contained in and entrained therewith; also for washing and humidifying air for heating and ventilating purposes.

30 Broadly stated, spraying apparatus embodying my invention and improvements, comprises a rotatable disk secured in which are spaced pins which project from a face thereof and are arranged at a distance from its axis of rotation, means for rotating said 35 disk, means for discharging liquid upon the face of said disk from which the pins project, the centrifugal action of the disk when rotated operating to project the liquid discharged upon the said disk outwardly across 40 the face thereof and to deliver it in the form of a thin sheet or film to the pins which project therefrom, whereby said sheet or film of liquid will be subjected to a combined beating and centrifugal action and will be projected outwardly in the form of a spray.

45 More specifically, the pins secured in the spraying disk are outwardly flared and are arranged in a circular series the center of which is substantially coincident with the 50 axis of rotation of said disk, the face of the disk against which the liquid is discharged being conical and the means for discharging liquid against the face of said disk comprising a nozzle which has pipe connection with

a source of supply of liquid under pressure 55 and which is directed upon the apex of the conical face of said disk.

In accordance with my invention, also, my improved spraying apparatus comprises the various other features, combinations of 60 features and details of construction herein-after described and claimed.

In the accompanying drawings, in which my invention is fully illustrated,

Figure 1 is a side view of a spraying apparatus embodying my invention.

Figure 2 is a face view of the spray disk.

Figure 3 is a sectional view of said spray disk and of the water discharge nozzle associated therewith, on the line 3—3 of Fig. 2.

Figure 4 is a sectional elevation showing my improved spraying apparatus installed in a trunk of a heating and ventilating system, said trunk being shown in cross and said spraying apparatus in rear end view; and

Figures 5 and 6 are views substantially similar to Fig. 1 illustrating modifications.

Broadly stated, a spraying apparatus embodying my invention and improvements 80 comprises a disk mounted so as to rotate freely with a high peripheral velocity, secured in which at points remote from its axis of rotation are spaced pins, which project frontwards from the face of said disk 85 and flare outwardly. In practice, I have found that highly satisfactory results are obtained with the attached ends of said pins spaced about five-sixteenths (5/16ths) of an inch apart and said pins flared outwardly at angles of about twenty-six (26) degrees to the axis of said disk. This relation may, however, be varied within a considerable range, and I do not, therefore, desire to limit myself to the exact relation shown or to any particular relation. My improved spraying apparatus also comprises means for imparting rotation to said disk and a nozzle having pipe connection with a source of supply of water under pressure, adapted for directing 90 a stream of water against the face of said disk, said nozzle preferably being mounted in axial alignment with the disk.

Referring now particularly to Figs. 1 to 4 of the drawings, in which I have shown what I now consider to be the preferable embodiment of my invention, 1 designates the spraying disk, which is rotatably mount-

ed on the rotor shaft 2 of an electric motor, indicated at 3. As shown, the means for mounting said spraying disk comprises a hub 4 formed on the rear side thereof provided with a bore to which the end of the rotor shaft 2 is fitted, said disk being secured to said rotor shaft by a set screw or other means.

The disk 1 is preferably made of cast bronze, the front face thereof being substantially conical in shape and comprising separate sections 5 and 6 separated by a circular shoulder 7, the outer section 6 being positioned rearwardly from the section 5. As shown, the face of the section 5 of the disk is slightly concave and the section 6 thereof comprises a surface 8 in which the spray pins 9 are secured, the attached ends of said spray pins being preferably spaced about five-sixteenths (5/16ths) of an inch apart from center to center, and the outer ends thereof diverging outwardly at angles of approximately twenty-six (26) degrees to the axis of said disk. The surface 8 of the disk is also rearwardly inclined at an angle which may be the complement of the angle of divergence of the pins 9 relatively to the axis of the disk. With this relation the pins 9 will extend substantially at right angles to the surface 8, which will facilitate drilling the holes in which the pins 9 are secured.

The rear side of the disk 1 is recessed in order to reduce the weight thereof as much as possible consistent with requisite strength, being shaped to form a circular shoulder 10 corresponding to the shoulder 7 on the front side of said disk, and formed in the body portion of the disk, so as to open through the shoulders 7 and 10, are what may be designated air ports 11, which extend substantially radially, and through which, in operation, the centrifugal action of said disk will produce currents of air which will enter the rear or inner ends of said air ports and will be discharged through the outer ends thereof, said currents of air becoming mixed and intermingled with the water discharged against the face of the disk 1, in operation, in the form of bubbles, which will facilitate the conversion of said water into spray.

Supported in front of the disk 1 is a water nozzle 12, the discharge end of which is directed against the apex of the conical face of said disk. Said nozzle has pipe connection with a source of water under pressure, as with an electrically driven pump, not shown.

The water discharge nozzle 12 is of such large size—say one (1) inch in diameter—as will provide an abundant water supply and will insure against choking of said nozzle by the deposit of dirt and sediment in operation.

In practice, I have used—with highly successful results—a spraying disk 1 substan-

tially nine (9) inches in diameter and pins 9 substantially two (2) inches long.

In Fig. 4 of the drawings, I have indicated my improved spraying apparatus as applied in use to a heating and ventilating system 70 by forced circulation, the spraying disk 1, motor 3, and water discharge nozzle 12 being mounted at the center of the air intake trunk of said system, indicated in section by the reference numeral 14. 75

In the operation of my improved spraying apparatus, the fan or blower for creating a current of air through the heating and ventilating system is first turned on, followed in turn by the motor 3, which drives 80 the spraying disk 1, and as soon as said spraying disk attains a desired speed, the pump, not shown.

Water discharged against the face of the spraying disk 1 from the water discharge 85 nozzle 12 will flow along the face of said spraying disk from its center outwardly, in the form of a thin sheet, atomization of which will be effected by the beating action of the pins 9 as the spraying disk 1 is rotated at high peripheral velocity, thus causing said pins to cut through or across the sheet of water passing outwardly along or over the face of said disk at almost imperceptible intervals, the centrifugal action of 90 said pins also operating to throw the atomized water particles formed thereby outwardly in a plane substantially at right angles to the axis of said spraying disk, the volume of water being sufficiently large 100 to form a spray of sufficient density and force to intercept and wash out all solid matter carried by the current of air which traverses the spray screen or curtain formed by said spraying disk. 105

I have found, in practice, that the atomizing action of the spraying disk is enhanced by the currents of air discharged outwardly along the face of the section 6 of said spraying disk through the air ports 11. 110

The spraying action of my improved spraying disk 1 is affected practically not at all by the impact of the water discharged from the water discharge nozzle 12 against the face of said spraying disk.

The face of the disk 1 is so shaped that water traversing the same will contact with the pins 9 at or closely adjacent to their attached ends, the flare of said pins and the centrifugal action due to the rotation of the disk causing any water which adheres to said pins to flow outwardly along the same and to be discharged from the outer ends thereof. The water flowing along the pins 9 will operate, in an obvious manner, to wash off therefrom any dirt or foreign matter contained in the water, which might otherwise catch on the pins 9 and obstruct the free passage of water between same.

As a result of extended tests and experi-

ment, I have found that a spraying apparatus of my invention comprising a single spraying disk 1 will form a spray screen or curtain having greater density and force than those produced by any spraying apparatus heretofore used; may be constructed at a smaller cost; is much more effective in operation; and will not become clogged or choked up as do the spray heads heretofore used.

While, as previously stated, I consider the spraying disk, shown in Figs. 1 to 4 and heretofore described, as the preferable embodiment of my invention, I do not desire to limit myself thereto, as the construction of said spraying disk may be variously modified with very satisfactory results in operation.

As one such modification, the shoulder 7 and the air ports 11 may be dispensed with, the conical front face of said disk being continuous from the center to the periphery of the disk, and being straight instead of concave.

This modification is shown in Fig. 5 of the drawings, in which 1' designates the spraying disk, 15 the straight, conical front face thereof, 9' the flared spray pins and 4' the hub for mounting spraying disk, said hub being provided with a bore to receive the rotor shaft.

As still a further modification of said spraying disk, I contemplate making the front face thereof plane.

This modification is shown in Fig. 6 of the drawings, in which 1² designates the spraying disk, the front face of which is plane and extends at right angles to the axis of rotation of said disk, 9² the flared spray pins, and 4² the hub for mounting said spraying disk.

As in the preferred form of the apparatus, the spraying action of the modification shown in Figs. 5 and 6, is produced by the combined beating and centrifugal action of the pins 9', 9², and not at all by the velocity of the water discharge against said spraying disk from the water discharge nozzle 12.

As shown, the spray pins 9 are round, but the shape of said pins is immaterial and they may be made of any desired shape within the scope and contemplation of my invention.

I claim:

1. In spraying apparatus, the combination of a rotatable disk, spaced pins which project from a face of said disk at a distance from its axis of rotation, means for rotating said disk, means for discharging liquid upon the face of said disk from which the pins project, the centrifugal action of the disk when rotated operating to project the liquid discharged upon said disk outwardly across the face thereof and to deliver it in the form of a thin sheet or film to the pins which pro-

ject from said disk, which will subject said sheet or film of liquid to a beating and centrifugal action and will project it outwardly in the form of spray.

2. Spraying apparatus as specified in claim 1, in which the pins secured in said disk are outwardly flared.

3. Spraying apparatus as specified in claim 1, in which the pins secured in said disk form a circular series the center of which is substantially coincident with the axis of rotation of said disk.

4. Spraying apparatus as specified in claim 1, in which the pins form a circular series and are secured in the disk adjacent to its periphery.

5. Spraying apparatus as specified in claim 1, in which the face of the disk against which the liquid is discharged is conical and the liquid is discharged upon the apex of said cone.

6. Spraying apparatus as specified in claim 1, in which the face of the disk against which the liquid is discharged is conical and slightly concave.

7. Spraying apparatus as specified in claim 1, in which the face of the spraying disk against which the liquid is discharged comprises separate central and marginal sections, the marginal section being arranged rearwardly from said central section and the pins being arranged adjacent to the periphery of said rear marginal section.

8. Spraying apparatus as specified in claim 1, in which the face of the disk against which the liquid is discharged comprises separate central and marginal sections, the central section being conical and the marginal section being arranged rearwardly from said central section, and the pins being arranged adjacent to the periphery thereof.

9. Spraying apparatus as specified in claim 1, in which the face of the disk against which the liquid is discharged comprises separate central and marginal sections, the marginal section being arranged rearwardly from said central section forming a shoulder between said sections, and said disk being provided with air ports which open through said shoulder and the inner ends of which open through the rear side of said disk and are disposed inwardly from the outer ends thereof.

10. Spraying apparatus as specified in claim 1, in which the face of the disk against which the liquid is discharged comprises separate central and marginal sections, the marginal section being arranged rearwardly from said central section forming a shoulder between said sections, and said disk being provided with air ports which open through said shoulder, said ports extending radially of said disk and their inner ends opening through the rear side thereof.

11. Spraying apparatus as specified in

claim 1, in which the face of the disk against which the liquid is discharged comprises separate central and marginal sections, the marginal section being arranged rearwardly 5 from said central section forming a shoulder between said sections, and the rear side of said disk being recessed to lighten the same and to provide a shoulder therein arranged inwardly from the shoulder formed in its 10 front face, said disk being provided with air ports opposite ends of which open through

the shoulders formed, respectively, in the rear and front sides of said disk.

12. Spraying apparatus as specified in claim 1, in which the means for discharging 15 liquid against said disk comprises a nozzle adapted to be connected with a source of supply of liquid under pressure.

In testimony that I claim the foregoing as my invention, I affix my signature this 30th 20 day of November, 1921.

EDWIN M. BASSLER.
